TELEVISION APPARATUS

Aloysius J. Cawley, Pittston, Pa.

Application May 23, 1930, Serial No. 455,127
Renewed May 24, 1935

3 Claims. (Cl. 178—6)

The invention relates generally to the electrical transmission of optical images. More particularly, it consists in forming a light image, and causing electrical fluctuations and modifications to be made in certain electrical apparatus hereinafter described. These electrical fluctuations are transmitted by wire or other conductor, or by electric waves to the receiving point where suitable modifications are made in an electrical apparatus associated with optical means, whereby an image of the original objects showing all of their movements is obtained. At the transmitter an element carrying a plurality of photoelectric cells is revolved rapidly in an image area. At the receiving station a similar member is revolved which carries a plurality of light sources or glow lamps which are illuminated in accordance with the image current or image modulated electric waves which are transmitted thereto from the transmitting station. The result is that the said light sources reproduce the original image.

A rotating contact member is provided which makes contact at the transmitting station with but one photoelectric cell at a time, while a similar member is provided at the receiving station which makes contact with but one lamp on the rotating arm at a time. Both cells and lamps describe a series of interrupted, concentric circles.

This contact member may be rotated at the same speed as the arms, but in a direction opposite thereto, or at a speed which is a multiple of the speed of the arm, as desired. The apparatus has therefore, great flexibility.

A very desirable modification is one which provides both photoelectric cells and light sources or glow lamps on the same rotating element at both the transmitter and receiver cooperating with their corresponding contact making or commutating elements. Thus, one image may be transmitted while another is reproduced in the same image field, giving two-way television, which differs from present methods in that the transmitted and received images are coextensive and also that the photoelectric cells and lamps are actuated alternately, so that it is impossible for the light of the glow lamp to be reflected from the face of the observer and retransmitted to the distant station.

This application is a continuation-in-part of my application Serial Number 380,202, filed July 22, 1929, for Television apparatus.

I attain the above objects by the apparatus illustrated in the accompanying drawing, in

which like reference characters have similar meanings, and in which,

Figure 1 is a plan view of a receiver. A fluorescent screen is also shown in this figure which may be used if desired to augment the action of the retina.

Figure 2 is an elevational view of a transmitter and illustrates the arms carrying the radially arranged photocells together with their contact means and revolving mechanism. A means for imparting any desired speed is also illustrated in this figure.

Figure 3 is an elevational end view of the apparatus for imparting variable speed to the transmitter or receiver illustrated in Figures 1 or 2.

Figure 4 shows an arrangement which combines the receiver and transmitter in a single unit at both of the stations. This constitutes an efficient two-way television apparatus. The photocells and neon lamps are mounted upon the same rotating element.

Figure 5 shows a detailed arrangement for avoiding simultaneous contact between a ridge on the contact disk with a photo-cell brush and a neon tube contact brush.

Figs. 6 and 6a illustrate the arrangement of the contact ridges on the disk 8.

Figure 1 is a plan view of the receiver, and illustrates that portion of the apparatus upon which the picture is to be displayed. A fluorescent screen in the form of an octagon is shown at 17. It may or may not be used, as it is not absolutely essential. It acts to retain a record of the flashes of the lamps which occur in the process of production of a visual image, and assists the eye in executing the function of persistence of vision. It retains the image from one revolution of the arm to another. In other words, it retains one of the complete pictures until the next is traced upon it in the form of fluorescent light. The screen is shown placed upright for viewing the picture. Behind the screen is an arm 3 carrying a row of neon lamps 4. Small incandescent lamps may be used, or any other glow lamp besides the neon, such as helium, etc. The arm corresponds to the diameter of the circle through which it rotates. This arm is pivoted and fixed in shaft 2, and is rotated by it. The neon lamps are shown disposed as one radius of the circle, that is, they occupy half of the arm. However, they may be placed all of the way across it, i. e., they may be placed alternately. Those shown are spaced and wherever there is a space, a lamp may be placed on the opposite side of the arm to illuminate what

would be a dark circle, when the arm is rotated. However, in the figure they are shown as being located on one side of the arm. Wire J designates a plurality of wires each of which connects to a lamp, and thus connects the lamp to a series of brushes. Each lamp is connected to a brush 7. This is done by means of short connecting wires. The lamps may consist of a single glass tubing containing a number of pairs of electrodes 6, or they may consist of a number of separate tubes provided with either internal or external electrodes 6. The row of contact brushes is located under the upper portion of the arm 3. The latter arm is made in two sections, the lower section having the brushes 7 attached in a stepped relation which is clearly illustrated at the left extremity of arm 3. It will be noted that the brushes are stepped so that only one is shown making contact with conducting ridges *i* at any one instant. The lower section of the arm has a stepped contour as shown for this purpose. The row of brushes is intended to be directly under the lamps as shown in the two other illustrations. Attention is particularly directed to the stepped arrangement of the brushes, as this is the factor that causes but one lamp or photoelectric cell to be supplied with electric current at any instant, and is very important. The ridges *i*, etc., are simply raised on the surface of the metal contact disk 8, and may be stamped in, if desired. A disk may be cut and stamped in a fraction of a second in manufacture. The thickness of disk 8 and the height of the ridges *i* need not be that shown. A very thin plate is desirable, as it may be rotated at a greater speed than a thick one. However, if desired, a heavy rim may be given to the disk, to give it a speed governing, speed uniformity, fly wheel effect. The arm need not be rotated at a speed greater than fifteen revolutions per second, but the disk may be geared to move many times as fast as that. Each multiple of the speed of the arm that the disk attains means greater definition to the image. For instance, if the disk moves three times as fast as the arm, there will be two extra sets of illuminated radii of the circle shown in Figure 1. This will be better understood later.

In the operation of the receiver, arm 3 is made to rotate at a uniform speed, say fifteen revolutions per second and is in synchronism with a similar arm at the transmitting station. Obviously, as the lamps 4 are illuminated, a series of luminous, interrupted, concentric circles will be described. Each lamp traces a circle consisting of bright flashes or dots. Each lamp is illuminated when it touches a contact ridge and extinguished when not in contact with the ridge, the circle described is therefore more or less interrupted. The intensity of illumination corresponding to the image to be produced is of course produced in the luminosity of the circle described by any particular lamp. The space between contact ridges *i*, etc., may or may not be covered with insulating material, such as bakelite, shellac, bitumen, pitch, mica composition, etc.; however, as the ridge is raised, air insulation may be used entirely.

It is evident that many different types of contact configurations may be given to the surface of the disk 8 besides that shown. Contact points may be used in various designs. It would be useless to illustrate all of them here, but it is intended to include them all in the appended specification and claims. The means for rotating the arm and disk in opposite directions is described

in connection with Figure 2. This and other means were described in connection with the above mentioned application.

Figure 2 shows a very compact arrangement for transmission. 1 is the motor, whose shaft 2a carries two long keys *n*. Upon the shaft is loosely mounted a disk V, having an opening therein to fit the keyed shaft. The hub Y of this disk is grooved to accommodate the handle *h*. It will thus be seen that the disk or wheel may be slid along the shaft by means of the handle *h*. This disk is in contact with the face of the wheel 3', and gives motion thereto. It may be shifted to any point on the radius of the wheel 3' desired, and thus to impart any degree of speed thereto desired. This means is simpler than that usually employed wherein the motor is shifted or moved bodily.

Several methods of operating the apparatus were described in the above mentioned application. Another means is as follows. Wheel 3' rapidly rotates the smaller wheel 9' mounted upon shaft 2', and this in turn rotates the larger member 10 of the pair of internal gears. The latter moves the internal wheel 10a, which is directly attached to disk 8, but which moves freely on shaft 2. Shaft 2 moves arm 3 to which it is firmly attached. Arm 3 carries the photoelectric cells 21. A cylindrical lens 16 may or may not be used to concentrate the light. Current passes through wire *a* to the commutator *c* insulated from shaft 2 by insulation *e*, through wire *d* into the hole in the shaft to wire 11, which supplies the current consecutively to the different photoelectric cells 21, according to which cell has its brush 7 in contact with the ridge *i*. Thus current can only pass through one photoelectric cell at any one instant. Current passes from the cell 21 to the connecting wire to brush 7, to ridge *i* or disk 8, to shaft 2, and thence to collector ring *k*, to brush *b*, to wire *m*, to external circuit. The receiver differs from the transmitter in that glow lamps or other light sources are used in place of the photoelectric cells.

If desired, in all of the apparatus illustrated, the connecting wire 11 may be eliminated, especially in connection with the neon tubes 4 in Figure 4. Neon lamps may be lighted by connecting them with but one terminal of a high frequency current circuit.

Figure 3 is an end view of the disk V and its hub Y, showing its manner of sliding on the shaft 2a.

Figure 4 illustrates a very compact system of two way television, which may be used in telephone booths, and the like. It consists of a transmitter and receiver similar to those described in Figures 1 and 2 and in the above mentioned application, with the distinction that the photocells and glow lamps are combined on the same rotating member at both the communicating stations. The two arms 3 and 3a move in synchronism, although it is to be understood that they may be many hundreds of miles apart. Means for rotating shaft 2 with its arm 3 and disk 8 were clearly described and illustrated in my application Serial Number 380,202, filed July 22, 1929. Such means are also described in connection with Figure 2 of this application. Any rotating means desired is therefore indicated at M and Ma. Therefore arms 3 and 3a as well as disks 8 and 8a rotate in synchronism at both stations. The disks and arms rotate in opposite directions.

In one station or telephone booth, arm 3a carries on one of its halves a series of photoelectric cells 21, and on the other half a series of neon tubes 4. The lens elements 22 and 22a form visual images at each station. Obviously, the photoelectric elements rotating on the arms act to both convert the visual image into image-varied current, and convert the incoming image-varied current into an optical image. A person facing the right side of the figure has his image impressed on photoelectric cells 21, which are supplied with energy by power supplying means indicated by the square D. This energy passes through brush 1a to disk 8, through ridge i and brush 1, through connecting wire to cell 21 to wire 11, through line wire 21a, to the other station (left side of the figure), to neon tubes 4, through wire to brush 1e, to ridge i on disk 8a, to brush 1b and to the other line wire 21b. The visual image of the other operator is produced by the neon tubes 4. The second operator, while viewing the image of the first, has in turn his image impressed upon the photoelectric cells 21b on arm 3 by lens elements 22 on his portion of the apparatus. This image is illustrated as being transmitted by means of wireless, in contrast to the wire transmission just described. t indicates the transmitting station, its energy being supplied by the usual apparatus indicated by the square labelled "Transmitting apparatus". The current from this passes to the cells 21b to wire, to brush 1f, to ridge i on disk 8, to peripheral brush 1c making contact with disk 8, and back to the power source at the transmitter. The energy is sent by radio waves from one antenna to the other, whence it is received and amplified by the receiving station r, supplied to disk 8 by its peripheral brush 1d and thence to ridge i, to brush 1g, to wire, to neon tubes 4, to common wire 11a and back to the receiving station amplifying circuit. The neon tubes 4 may be of a type which exists on the market today. They may be illuminated by simply pressing them against an electrode carrying a high frequency alternating current. But one connection is necessary to light them. The photoelectric cells 21 are of the cylindrical type and are made very small. Head and shoulder pictures are now transmitted by television in practice, as a 48 line picture is capable of transmitting nothing more satisfactorily on account of lack of detail. Head and shoulder pictures will be sufficient to carry on telephone conversation accompanied by television. The system herein illustrated also possesses the great advantage that the speaker is shown on the receiving portion as looking directly at the one spoken to and not away from him, as is necessary in other types of television.

Another feature of the apparatus is that it may be used to transmit colored pictures. Each alternate photoelectric cell 21 may be provided with a suitably colored glass, for instance, the first having blue-violet and the second having an orange-red. The corresponding neon tubes will be provided at the receiving station, i. e., the orange-red will be connected to a neon tube, while the blue-violet will be connected with a mercury or helium, or argon, etc., glow tube. Instead of connecting and equipping alternate tubes in the same row as described, a special row on a separate arm or disk may be provided. For instance, there will be a radial arm carrying only blue-violet photoelectric cells, another arm for orange-red, another arm carrying neon glow

lamps and still another arm carrying mercury or helium lamps at each station, i. e., either at the right or left side of Figure 4.

The above figure shows that the system is adaptable to wire or to wireless systems. 5

Figure 5 illustrates the fact that the upper brush 1 in Figure 4, which makes contact for the neon receiving tubes with ridge i, is in contact with this ridge, while the lower brush 1 (which makes contact for the photoelectric cells) is not 10 in contact. In other words, there is an alternate making of contacts with the glow tubes and the photoelectric cells. There is not a simultaneous making of contact. This is very important, as the system is positively two-way in character. 15 This prevents the photoelectric cells from receiving the light of the glow lamps that may be reflected back from the face of the operator. The glow lamps in an extremely small fraction of a second, flash a portion of the image and are then 20 cut out of circuit. Then the photocell is cut in circuit and receives a part of its image, and so on. Of course, separate contact disks 8 and separate circuits may be provided if desired for each radial row of glow tubes and each row of photo- 25 electric cells.

It will be seen in all of the above apparatus that disk 8 of the receiver is charged at all times during which a photo cell is connected at the transmitter to its disk, with the image varied 30 current, and is fed to the lights one at a time in what may be termed "radial strokes". On arm 3 there is a row of brushes 1 etc., which make contact with ridges i, etc., of disk 8. Those ridges are so designed, as shown at the left of Figure 1, 35 that but one brush 1 makes contact at any one time or instant with ridge i, and this means that only one photoelectric element such as 4 will produce a corresponding intensity of illumination in lamp 4, in accordance with the intensity of 40 illumination in that portion of the image that is in relation with the corresponding photoelectric cell at the transmitter.

In studying the configurations of the disk 8, it will be seen that as arm 3 is rotated at say fifteen 45 times per second, and remembering that but one brush 1 can be brought in contact with ridges i, etc., at a time, and consequently but one light will be illuminated at a time, there will be a series of broken, concentric circles of luminosity, each 50 corresponding to the path of a neon lamp on arm 3, the breaks being due to the intervals between the ridges i. It is also remembered that there will be a blending or fusing of more or less of the luminous interruptions in the circles. Figure 1 at 7, clearly shows that the brushes 1 are staggered or stepped with reference to ridge i, so that at any instant only one photoelectric element will be activated. It is impossible to show them in their exact proportion, as the brushes 55 are very small in comparison to the disk or arm. Disk 8 may be in the form of a sprocket wheel, or as a disk having wires placed radially in lieu of ridges i.

It will therefore, be seen that as arm 3 is rotated at say fifteen times per second, the image will appear as a diffused, illuminated electric image in which there is a radial building up of the diffused, interrupted, concentric circles. The radial illumination will slant somewhat away 70 from a true radius, due to the stepping of the contact brushes as described above.

Disk 8 may be designed as stationary and attached to the frame of the apparatus, as in the form of the invention described and illustrated 75

in connection with sheet 1 of the drawing. It may also be made stationary at will by removing any one of the gear wheels which cause its motion. Its rotation is, however, a very important feature of the apparatus. It is of course rotated in a direction opposite to that of the arm 3, giving a relative speed of both elements which is equal to the sum of their speeds. In the more expensive forms of the apparatus, disk 8 will be given a speed of rotation that is many times that of arm 3, if desired. If it revolves twenty-one times as fast as arm 3, the relative speed is 315 rotations per second, if the arm moves at 15 R. P. S. This would mean twenty one new sets of radial lines added to the image, equaling if not exceeding the luminous streaks of the pin-hole spiral disk. All of the illumination of all of the lamps is more constantly in use in contradistinction to the infinitesimally small fraction used in other methods. A thin metal disk with stamped ridges on its surface is desired, as such are much cheaper than the more elaborate commutators. They can be stamped by the thousands at very small cost.

25. Instead of the glow lamps of any type, incandescent lamps may be used if desired. Attention is directed to the type of neon tube which is illuminated by being placed in contact with but one electrode carrying a high frequency current.

30. Their cost is very small. The invention, of course, includes any form of lamp or tube. Tubes with a single pair of internal electrodes, or a large single tube with many pairs of electrodes may be used.

35. Having described my invention, I claim as new and desire to secure by Letters Patent:

1. A combined television transmitter and receiver consisting of a motor, optical means for forming an image, a rotatable element in the plane of said image operatively connected to said motor to be rotated thereby, a group of photoelectric cells and a group of glow lamps carried on said rotatable element and being rotatable in said image plane thereby, said image plane being of the order of magnitude of said rotatable element, a transmitting conductor connected to one terminal of each of said photoelectric cells, a receiving conductor connected to one terminal of each of said lamps, a plurality of contact 40 brushes connected one to each of said photoelectric cells and said lamps, a commutator capable of making contact with but one of said brushes

at a time, a transmission circuit connected to said transmitting conductor and to said commutator and a receiving circuit connected to said receiving conductor and to said commutator in order that said photoelectric cells shall be intermittently connected to said transmission circuit and that said lamps shall be alternately connected to said receiving circuit that images may be transmitted and received in the same image area.

2. A two-way television apparatus consisting of optical means for forming an image, a rotatable element within the plane of said image and substantially coextensive therewith, a group of photo electric cells and a group of light sources 15 borne on said rotatable element and so arranged thereon as to describe a plurality of paths coextensive with said image plane, said image plane being of the same order of magnitude as said rotatable element, means for consecutively and 20 independently collecting the image varied current produced in said photoelectric cells, means for consecutively and independently supplying a second image varied current to said light sources in order that an image may be transmitted and 25 received in the same image area and means for rotating said rotatable element within said image plane.

3. A two-way colored television apparatus consisting of means for forming an image, a rotatable 30 element within the plane of said image and substantially coextensive therewith, a group of photoelectric cells and a group of light sources borne on said rotatable element and so arranged thereon as to describe a plurality of paths coextensive with said image plane, said image plane being of the same order of magnitude as said rotatable element, certain of said photoelectric cells being sensitive to light of a specific color and certain others of said cells being sensitive to light 40 of another color, certain of said light sources emitting light of a specific color and certain others of said sources emitting light of another color, means for independently collecting the image varied light produced in said photoelectric 45 cells, means for consecutively supplying a second image varied current to said light sources in order that an image may be transmitted and received in the same image area and means for rotating said rotatable element within the said 50 image plane.

ALOYSIUS J. CAWLEY.
